DRIP TUBE DISPENSING UNIT

John E. B. Shaw, Chicago, Ill.

Application January 22, 1944, Serial No. 519,377

2 Claims. (Cl. 128—214)

This invention relates to a unit adapted to provide air to a bottle containing liquid, so that the liquid therein may be dispensed and in the same combination providing the features and advantages of a visible drip tube.

It is among the objects of my invention to provide a unit which may readily be attached to a container containing liquid, said unit having means for providing air for the bottle to displace the liquid therein and permit the liquid to flow therefrom. It is also among the objects of my invention that my unit shall be so constructed that the air will pass through liquid in a wash chamber before it passes into the container. Another object is to so construct my unit that it also functions as a visible drip tube. Thus I have a combination unit adapted to provide washed air to dispense liquid from a sealed container and also to visibly show the flow through a drip tube.

Heretofore users of a dispensing cap could determine the flow of liquid by watching the bubbles appearing on the top surface of the liquid in the container. This was difficult and also uncertain. Tests have been made showing that when the bottle was one-third emptied that the bubbles became irregular and therefore this method of gauging the flow was unsatisfactory.

Another way to determine the flow of the liquid was to obtain and place a Murphy drip or the like in the line of the parenteral administration tubing. This involved a separate member and the problems of assembling and cleaning of the parts. During cases of emergency, delay caused by this cleaning and assembling of separate parts is serious, and its avoidance is desired. With my unit having a drip tube portion this need of assembling and the consequent delay is avoided.

My invention also contemplates such other objects, advantages and capabilities as will later more fully appear and which are inherently possessed by my invention.

While I have shown in the accompanying drawing a preferred form of my invention, yet I wish it understood that the same is susceptible of modification and change without departing from the spirit of my invention.

Referring to the drawing, Fig. 1 is an elevational view of my device in use; Fig. 2 is a top plan view of my drip tube dispensing unit; Fig. 3 is a side elevational view; Fig. 4 is an elevational sectional view on line 4—4 of Fig. 2; Fig. 5 is an elevational sectional view with the parts separated; Fig. 6 is a detailed sectional view

on line 6—6 of Fig. 3 and Fig. 7 is a detailed view on line 7—7 of Fig. 5.

The embodiment selected to illustrate my invention comprises an upper portion 10 made of rubber or any other suitable material, adapted to be attached to a bottle or other suitable container 11 containing sterile liquid to be dispensed for parenteral injection. The upper portion 10 has a top 12, depending rounded side walls 13 and an open bottom 14. An air inlet opening 15 extends through top 12 into the hollow interior 16. Extending downwardly from top 12 within interior 16 is a housing 17 having a substantially straight depending side wall 18 extending across said interior 16, and meeting a depending rounded side wall 19 spaced from side walls 13. A liquid inlet opening 20 extends through top 12 into the hollow interior 21 of housing 17. A tip 22 extends below the bottom 23 of housing 17 and has a liquid outlet opening 24 therethrough communicating with the interior 21 of housing 17.

A lower portion 25 is constructed of transparent material, preferably plastic or glass, and has an air wash chamber 26 having a closed bottom 27, an open top 28, an outer rounded side wall 29 having an air inlet hole 30 therethrough leading from the interior 31 of air wash chamber 26 to the atmosphere or other air or gas supply. Spaced from said air wash chamber 26 is an abbreviated overflow member 32 having side walls 33, a closed bottom 34 and an open top 35 extending above hole 30. Adjoining said air wash chamber 26 but separated therefrom by a common wall 36 is liquid flow drip tube chamber 37 having a rounded side wall 38, an open top and a closed bottom 39, having a tip 40 extending therebelow with an opening 41 therethrough.

Upper portion 10 is adapted to be removably attached to lower portion 25. The diameter of the bottoms of rounded side walls 13 of upper portion 10 is larger than the diameter of rounded side walls 29 and 38 of lower portion 25 so that upper portion 10 may be moved down over the top of lower portion 25. In this position rounded side wall 19 and straight side wall 18 of housing 17 fit snug against the inner surfaces of rounded side wall 38 and wall 36 of liquid flow chamber 37 to form a seal therewith. Upper portion 10 is formed with a slight inward taper so that the upper ends of walls 38 and 29 of lower portion 25 contact the inner surfaces of side walls 13 of upper portion 10. In this position tip 22 extends down within the hollow interior of liquid flow chamber 37 and is visible.

In use, my device with the upper and lower portions 10 and 25 in assembled position, is attached to the open top of a container 11, containing a sterile solution for parenteral injection. The bottle 11 is then inverted, and its swingable bale 42 is placed on a standard 43.

Air coming from the atmosphere passes through air inlet hole 30 into air wash chamber 26 and through its open top 28, then through air inlet opening 15 into the container 11. This permits flow of the liquid in container 11 down through liquid inlet opening 20 into the interior 21 of housing 17, and thence through liquid outlet opening 24 in tip 22 to liquid flow chamber 37. As the liquid drips from opening 24 in tip 22 into liquid flow chamber 37, its dropping or rate of flow is visible. The liquid passes downwardly from liquid flow chamber 37 into tip 40 and out opening 41 therethrough into tubing 44 attached to tip 40, thence through needle 45 attached to the lower end of tubing 44 into the patient. A clamp 46 is attached to tubing 44 for regulation of the flow of the liquid.

Liquid also passes downwardly through air inlet hole 30 into wash chamber 26, so that air coming into wash chamber 26 passes through said liquid in wash chamber 26 before it passes through opening 30 into the container 11. Overflow chamber 32 normally takes care of any liquid over-flowing from wash chamber 26.

Thus in combination my construction provides washed air for the container, dispenses the liquid in the container, and provides a visible drip tube for calculating the rate of flow of the liquid for the parenteral injection.

Having thus described my invention, I claim:

1. In combination with a container having sterile injection solution therein, an air filter drip tube dispensing device, comprising an upper portion adapted to be attached to said container, said upper portion having a closed top, side walls, an open bottom and a hollow interior, said upper portion having an air inlet opening extending through said closed top into the hollow interior and also communicating with the interior of said container, said upper portion having an integral housing extending downwardly from said top within said hollow interior, a drip extension integral with and extending below said housing and said side walls and having an opening therethrough communicating with the interior of said housing, said closed top also having a liquid outlet opening communicating with the interior of said container and leading into the interior of said housing, and a transparent lower portion having an air wash chamber with a closed bottom, an open top, and side walls having an air inlet opening leading to the atmosphere, said lower portion also having a combined liquid flow and drip tube chamber having an open top, side walls, a bottom, and a tip extending below said bottom, said bottom and said tip having a liquid flow opening, said tip adapted to receive paren-

teral injection means, said upper portion adapted to be attached to said lower portion, with the housing and drip extension of said upper portion positioned within said combined liquid flow and drip tube chamber of said lower portion, and said air wash chamber of said lower portion in communication with said hollow interior and said air inlet opening of said upper portion, so that air may flow from the atmosphere through said air inlet opening of said air wash chamber into said air wash chamber, through said hollow interior and said air inlet opening of said upper portion into said container to permit liquid to flow from said container down through said liquid outlet opening in said upper portion into said housing, and out said housing through the opening in the extension of said housing directly and visibly into said combined liquid flow and drip tube chamber and thence out through the tip of said liquid flow chamber into the parenteral injection means; for a parenteral injection, said drip extension of said housing of said upper member extending downwardly and visibly within said transparent combined liquid flow and drip tube chamber so that the flow of liquid therefrom is visible for gauging the flow thereof.

2. In combination with a container having sterile injection solution therein, a drip tube dispensing device comprising an upper portion adapted to be attached to said container, said upper portion having an air inlet opening therethrough communicating with the interior of said container, said upper portion also having a liquid flow means communicating with the interior of said container and having a hollow tip extending below the bottom of said upper portion, and a lower portion having an air supply portion and a transparent combined liquid flow and drip tube chamber, said chamber having an apertured tip adapted to receive parenteral injection means, said upper portion adapted to be attached to said lower portion with said air supply portion of said lower portion in communication with said air inlet opening of said upper portion, and said liquid flow means of said upper portion in communication with said combined liquid flow and drip tube chamber of said lower portion, so that air may flow from said air supply portion of said lower portion through said air inlet opening of said upper portion into said container to permit liquid to flow from said container down through said liquid flow means in said upper portion directly into said combined liquid flow and drip tube chamber of said lower portion and thence out through said apertured tip into said parenteral injection means for a parenteral injection, said hollow tip of said liquid flow means of said upper portion extending downwardly within said transparent combined liquid flow and drip tube and being visible therein so that the flow of liquid therefrom is visible and gaugeable.

JOHN E. B. SHAW.
